United States Patent Office

Des. 218,036
Patented July 14, 1970

218,036

WATER SEPARATOR FOR AIR HANDLING SYSTEMS

Ludwig A. Schirm, Huntingdon Valley, Pa., assignor to Harold E. Sweeney Corp., Philadelphia, Pa., a corporation of Pennsylvania

Filed Feb. 5, 1969, Ser. No. 15,641

Term of patent 14 years

Int. Cl. D23—04; D25—03
U.S. Cl. D23—163

Fig. 2.

Fig. 1.

Fig. 3.

FIG. 1 is a perspective view of a water separator for air handling systems, fragmentarily shown for ease of illustration;

FIG. 2 is an elevation as seen from the rear and opposite side of FIG. 1; and

FIG. 3 is a fragmentary bottom plan view of the water separator.

I claim:

The ornamental design for a water separator for air handling systems, as shown and described.
